LENS FOR LIGHTING FIXTURES

Viktor Schreckengost, Cleveland Heights, Ohio, assignor
to Halophane Company, Inc., New York, N.Y., a cor-
poration of Delaware

Filed Dec. 19, 1960, Ser. No. 63,263

Term of patent 14 years

(Cl. D48—16)

FIG. 1 is a plan view of a lens for lighting fixtures showing my new design;

FIG. 2 is a side elevation thereof; and

FIG. 3 is a perspective view thereof.

I claim:

The ornamental design for lens for lighting fixtures, as shown.
